UNITED STATES PATENT OFFICE.

ALPHONSE WALTER, OF NEW YORK, N. Y.

DESIGN FOR A STORAGE AND DISPLAY CASE.

SPECIFICATION forming part of Design No. 29,236, dated August 16, 1898.

Application filed July 16, 1898. Serial No. 686,157. Term of patent 7 years.

To all whom it may concern:

Be it known that I, ALPHONSE WALTER, of the city of New York, borough of Manhattan, in the county of New York and State of New York, have invented and produced a new and original Design for a Storage and Display Case, of which the following is a specification, reference being had to the accompanying drawings, forming a part thereof, in which—

10 Figure 1 is a plan view of a storage and display case embodying the features of my design, and Fig. 2 is a longitudinal vertical section taken practically on the line 2 2 of Fig. 1.

The leading feature of the design consists 15 in a series of partitions A, located within the case, each partition having wings B upon each side face, the wings being at right angles to the body of the partitions. The wings are correspondingly located upon all of the 20 partitions between the ends of the case and are arranged in pairs. All partitions appear

to rest upon strips C, which are at right angles to the winged partitions, and the said strips appear below the partitions at the wings thereof, the wings of the partitions being in 25 longitudinal alinement with the strips.

The design in its entirety represents a series of pockets within the case, the pockets being closed upon two opposing sides and partially open on the other two opposing sides. 30

The detail feature of the design consists in depressions in the inner faces of the case, into which the ends of the partitions apparently enter.

I claim—

35 The design for a storage and display case, as herein shown and described.

ALPHONSE WALTER.
